(57) **CLAIM**

The ornamental design for a fan with light, as shown and described.

DESCRIPTION

FIG. 1 is a top, rear and left side perspective view of a fan with light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2;

FIG. 12 is an enlarged view of portion 12 in FIG. 3;

FIG. 13 is an enlarged view of portion 13 in FIG. 4;

FIG. 14 is an enlarged view of portion 14 in FIG. 5;

FIG. 15 is an enlarged view of portion 15 in FIG. 6;

FIG. 16 is an enlarged view of portion 16 in FIG. 7;

FIG. 17 is an enlarged view of portion 17 in FIG. 8; and,

FIG. 18 is an enlarged view of portion 18 in FIG. 8.

The broken lines show the portions of the fan with light that form no part of the claimed design. The dot-dash-dot broken lines are for the purpose of annotating the enlarged views only and form no part of the claimed design.

1 Claim, 18 Drawing Sheets
